(57) **CLAIM**

We claim the ornamental design for a cab tilt device for a construction machine, as shown and described.

DESCRIPTION

FIG. 1 is a front, top and left side perspective view of a cab tilt device for a construction machine showing our new design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; and, FIG. 8 is a cross-sectional view thereof taken along lines 8-8 in FIG. 2. The hatchings shown in FIG. 8 are for illustrative purpose and form no part of the claimed design.
